(54) **PRESS, COTTON & HAY**

(76) Inventor: **Robert Triplett**

Robert Triplett. County of Daviess. Kentucky.

Litters Patent.

The schedule referred to in these Letters Patent and making part of the same containing a description in the words of the said Robert Triplett, County of the improvement in the machine for pressing Hay, Section 8:

To all to whom these present, shall come.

Be it known that I Robert Triplett of the County of Daviess and State of Kentucky, have invented a new and useful improvement in the pressing machine, for pressing straw, Hay, and other articles, and that the following is a full and exact description of the construction and operation of the machine as invented by me, and called the Horizontal Press.

The object of this invention is to do the pressing horizontally, instead of pendularly, as is usual, and to press both ends, of the straw instead of at one, thereby accomplishing double the usual work in the same time, this is accomplished in three different ways. First by a cast iron wheel with a screw nut or a female screw in the hub thereof, and a male screw passing through the same;

the hub resting in two plumbum blocks, one on each side of the spokes, fixed into hard blocks, rising the head of the hub completely, except an opening sufficient for the straw to pass through, if the ends of the hub as well as on the circumference only so much is allowed to bear (the balance being hollowed out) as may be requisite for strength. This is by means of friction, the wheel being cogged and geared into wheels driven by steam, water or horse power, with motion with a velocity and strength according to the pressure and power applied to it.

In passing it is necessary to particularize, so every will right understand it, that the simplest place is by a perpendicular shaft, resting with its lower end upon a bridge tree across the pressing box, the upper end passing through a floor above the pressing box, and confined by two timbers (part of the floor) with a half round cut out of each meeting about a neck cut into said shaft. Through the upper end of the shaft a hole is cut of sufficient size for a lance of any given

ought to bear the power applied to it; on the said shaft below, is a wheel or a ⁶⁶box
and head to work into the nut wheel. The upright shaft being put in motion by
horses at the end of the box, turns the vertical nut wheel, and the screw being
fastened at each end to followers, so as to prevent its receding, it must pass to
and fro, as the vertical wheel rotates, and so the pressing in boxes prepared for the
purpose, at each end of the screw, see the drawing —

The next is upon the same plan with this difference only. The screw instead of
working into the wheel, forms the axle of the wheel & is fixed firm into the hub.
It is a small space on each side of the hub. There are no threads but the shaft of
the screw, is left smooth, and these smooth spaces receive in plumbmer blocks on
each side of the hub as before described. on each end of the screw is a nut or
a strong moveable timber of the same size of the pressing follower, which works in
the press box. From this moveable timber to said follower are two rows of suffi-
cient steps to bear any pressure which may be required. These rows extend
from said moveable timber when at the top of the wheel, to said follower
beyond the end of the screw, say ten feet. At the screw receding, it
passes this frame toward the wheel, on one side and drives it from it on
the other, and alternately, receding at either end, see the drawing —

The first of these plans requires but half the length of screw of the latter
and not much over half the length of press box. It also dispenses with the
timber in which the nut screw as well as the axles, — but it has more friction by
receding on the hub than the, latter which recedes on a small axle.

The latter advantage however is due unequal to the disadvantages, and therefore
prefers the first plan. — The third plan is as follows. This screw is
to be very large and may be made of wood. The threads work into eyes in a
timber below, called the "slide". This slide is of substance sufficient to bear
any pressure which may be put on it, wide enough to admit of eyes two feet
across to fit the space between the threads of the screw, and runs in a chamber
of the length of the screw or any desired length made just to fit it. It is
followed a little at the sides and bottom to avoid friction the outer edges
only touching. The bottom of the chamber is of a thickness equal to the
space between the top of the slide and the top of the press box, thereby leav-
ing it (the slide) exactly in the centre of the box. The top surface of the

slide is hollowed to fit the circumference of the screw, so are the tops of the cogs, and the cogs are put into the slide at the same angle with the threads of the screw, so as to fit well and closely into the spaces. A quidgen at each end of the down shaft, (which should be about eight feet long) fits into a head block, inserted into the prop box & turned into posts on the outside. All in the strongest possible manner; at one end of said shaft are bevelled cogs which work into bevelled cogs in an upright shaft, the quidgen from which fits into the same head block, into which the quidgen from the screw shaft is inserted.

This upright shaft passes through the floor above $\frac{1}{2}$, is inserted as the other are — see the drawings for a more clear comprehension of this plan.

In this plan the friction is considerably less than in either of the other two, as the pressing power is against the end of a quidgen instead of being against the end of the surface of the hub. ... The friction against the cog is not greater than that of the screw in the nut, just two feet of cog surface, in a slide eight feet in length, is less than the surface for the whole circumference two feet in length, and yet eight feet of cog surface (being about eleven cogs of two feet each) will give any desired strength, the cog being three inches thick, and showing only two inches above the slide, but below this size, the iron screw, is compared with the wooden, I am not prepared to say that the same power on the iron would not do more than on the wooden screw, in the size of cog power the wooden has the advantage, it may be made and the whole machinery belonging to it in any section of country by an ordinary engineering mechanician. The iron screw must be at least six inches in diameter and twelve feet long. If of wrought iron (and I am not sure that cast iron will suffice) it would be very costly. These considerations induce me to adopt for my own use the wooden screw, to a prop which I am now erecting.

... get the shaft upon which the thread is cut three feet in diameter, cut the thread four inches wide and two deep, this space three inches, one revolution thereof drives the slide forward seven inches, the space is less than the thread because, the face of a cog presented to a wooden thread, is stronger than the thread. The prop box should be about thirty seven feet long, eight feet in the centre for the screw, three feet for the two

head blocks, each being a foot and a half thick. ~~the~~ feet for the followers, each being a foot thick & two feet for two false followers, the two latter to be between the bale & the followers, with two large grooves in them on the side next to the followers, for cramps (like square staples) to take hold of the false followers, by means of screw bolts, passed down through these grooves, the arms catching back and jointed over the end of the prop. When the bale is pressed these screw bolts are passed down, laps put on below and wedges driven between the cramps and the prop, to tighten the false followers, or if the expense be not an objection, the sides of the prop can be extended as represented in the drawing -- A false follower with a tongue at each end put into grooves in said sides, the cramp embracing it and extending its arms into the prop. A screw through this follower with the head inward, the screw pointing outward and passing through an end piece and through the hub of a wheel on the outside with a screw nail therein, now when the cramps are fast or loose of this wheel tightens the false followers, in other words pressing the bale so as to release the wooden wheel may now return to prop upon the other side. The spaces in the pressing chamber, for occasions, the vehicle to be pressed should be ten feet in length, together twenty feet then the two end pieces of the prop a foot each makes thirty seven feet this completed, the length of the prop proper. — But if the appendages of ~~or~~ the cramps are added then there must be two feet for the cramp followers. two feet for two spaces of five feet each, and two feet for two end pieces of a foot each — making an addition of fourteen feet, making the length of the prop, fifty one feet to the wheel and about four feet more for boxes to enclose the hub of the wheel, so as to hold it to its place. If the wheel be small it may revolve within the sides of the box, extended but if turned larger the boxes must be extended. Another advantage in this wheel and the cramps is that by passing a chain round the wheel and over pulleys, then crossing the chain and passing it around the upright or driving shaft, you obtain the power of the horse to work the iron screw, as the wooden slides revolve, and by this means the pressure on the bale will be many fold greater than the foot pressing, it is only necessary to have the iron screws and cramps strong enough, as well.

as the pulleys and chain, to prop the bale is hard as not to require replacement for shipment. The pressing box is placed high enough from the ground floor to allow the bale when pressed to pass ^{out} below, ~~out~~ high enough to allow the door below to open without touching the ground. The lower side or bottom of the pressing chamber, is floored of course except so much as may be necessary for the bale to pass out at. This space is filled as is the top by doors, which are hung with hinges, which might be made strong enough so might the doors & a bolt be on the opposite side to withstand the pressure but to guard against all doubt on that score, I shall construct that which I am erecting as I have had the model made, with safety and bars. The advantage of this press over the usual one is, that it presses at both ends. That by being horizontal while the operation of pressing is proceeding on one side the other being empty can be filled and prepared to receive the presser as soon as it is completed on the opposite side, even the delay for removing and opening the bale is avoided by the aid of the cramps, which are fixed in a few minutes, on the drawing of the cramps as clasping the followers. detached from the press, & see them also in the press, — see a top view of the press in the drawing with the doors open on one side & closed on the other, see the upright shaft working into the screw shafts & the screw working into the slides, as detached from the press top. see at the end of the slides, the follower with holes through it, for screwing it to the slides. see the false follower, ready to be laid loose against the follower with grooves for the cramp bolts on one side & for the baling wire on the other, see the corresponding grooves, for the baling wire in the press chamber; then see the drawing of the whole machine together and that together with this description will give a complete idea of the whole machine. —

I claim as my invention, the horizontal pressing box, and cogged slides therein, whether moved by a screw or other machinery,

I claim also as my invention the application of the screw, to the side cogged slides. — I claim also as my invention, the horizontal pressing box, with the screw passing through the hub of a wheel, which by revolving different ways covers the screw when attached to follower

at either end to pass first at one end and then at the other.

I claim as my invention, the screw laid horizontally in a packing box, with a wheel in the centre thereof revolving upon the screw shaft as an axle, the same being fast in the hub of the wheel, and a small smooth surface of the screw shaft on each side of said hub forming the axle - nuts being fastened on each end of said screw to which is attached the pressing power as hereinbefore described.

All the foregoing I claim as various modifications and applications of the same principle invented by me.
